UNITED STATES PATENT OFFICE.

HENRY B. JENNINGS, JR., OF LEESBURG, VIRGINIA.

LOOSE-LEAF BINDER.

Application filed July 6, 1925. Serial No. 41,784.

This invention relates to improvements in loose leaf binders and has as its general object to provide a loose leaf binder possessing features especially adapting it for use by ministers, professors or teachers, and others who desire or are required to have at hand texts or other matter of a permanent nature, and similar matter of a more or less temporary nature. As a concrete example, the binder is especially adapted for use by ministers and may comprise the text of the Bible in loose leaf form retained in the binder in such a manner that memorandum leaves may be interposed between groups of Bible text leaves to bear memoranda and permit of notes being made, so that in delivering a sermon, the minister may readily refer to biblical texts and as readily refer to the memoranda or notes which he has made relative to the subject of his discourse.

Another object of the invention is to provide a loose leaf binder so constructed that when the binder is open, the same will lie flat so that the temporary leaves may be readily consulted or written upon without the inconvenience which would be experienced if these leaves were so held in place as not to assume a flat form or position.

Another object of the invention is to provide a loose leaf binder which will be automatically locked when it is closed, so that it will not have a tendency to assume an open position when it is being carried or is laid upon a desk or the like.

Another object of the invention is to provide a loose leaf binder so constructed that whether the same be open or closed, the margins of the leaves bound thereby will be in exact registration, so that the binder will present a neat appearance, and fraying of the margins of the leaves will be practically prevented.

Another object of the invention is to so construct the binder that, as the same is opened and closed, the relative movement of the bank of leaves will be uniform and there will be no distortion or disarrangement of the leaves.

Another object of the invention is to so construct the binder that the temporary leaves may be readily removed, either individually or collectively, without in any way disturbing the relatively permanent leaves, the invention further contemplating a con-

struction in which the so-called permanent leaves may be readily and conveniently removed and replaced without disturbing the temporary leaves.

Another object of the invention is to provide a loose leaf binder embodying a novel construction of back which is of such character as to preclude the likelihood of any metallic parts coming in contact with a surface upon which the binder may be placed, the construction, furthermore, being such that all of the mechanical parts are substantially concealed.

In the accompanying drawings:

Figure 1 is a plan view of the loose leaf binder embodying the invention, spread open.

Figure 2 is a transverse sectional view taken substantially on the line 2—2 of Figure 1, looking in the direction indicated by the arrows.

Figure 3 is a detail view in elevation of the lower end of the binder back.

Figure 4 is a similar view illustrating the binder closed.

Figure 5 is a vertical sectional view taken substantially on the line 5—5 of Figure 1, looking in the direction indicated by the arrows.

Figure 6 is a sectional view taken substantially on the line 6—6 of Figure 5, looking in the direction indicated by the arrows, only one side of the binder being shown.

Figure 7 is a detail transverse sectional view taken substantially on the line 7—7 of Figure 1.

Figure 8 is a fragmentary perspective view illustrating a portion of the means provided for retaining the temporary leaves of the binder in place.

Figure 9 is a fragmentary, group perspective view illustrating certain elements of the binder in position about to be assembled.

Figure 10 is a sectional view taken substantially on the line 10—10 of Figure 9, looking in the direction indicated by the arrows, and illustrating the respective parts assembled.

Figure 11 is a perspective view of one of the retaining members for retaining in place the permanent leaves of the binder.

Figure 12 is a perspective view illustrating a modified form of latch for holding the binder closed.

Figure 13 is a plan view of the modified latch structure, illustrating the latch member engaged with its keeper.

The binder consists essentially of two cover leaves indicated by the numeral 1, which leaves are of flexible leather, inner cover leaves indicated by the numeral 2, which are preferably of cardboard and which lie against the inner faces of the outer cover leaves 1 and may be secured thereto to somewhat stiffen the said outer cover leaves, and a back 3 which is likewise formed of flexible leather and which is folded at opposite sides of its longitudinal median line to provide an intermediate portion 4 constituting the back proper, and flaps 5 which are disposed against and are in marginal registration with flaps 6 provided by turning the inner marginal portions of the cover leaves 1 substantially at right angles to the body portions of the leaves. The inner margins of the inner cover leaves 2 preferably terminate substantially at the folds defining the flaps 6 of the outer cover leaves 1, and said flaps 6 and the flaps 5 are secured by rivets or other suitable securing means 7, to metal backing plates 8, the rivets being secured likewise through plates 9 which are disposed against the inner faces of the flaps 6, the plates 8 being disposed against the outer faces of the respective flaps 5, as clearly shown in Figures 2 and 7 of the drawings. The outer marginal portions of the plates 9 are bent as at 10, to provide right angularly extending wings 11, folded back upon themselves as at 12 so that these wings are of two ply construction. As illustrated most clearly in Figures 3, 4 and 5 of the drawings, and for a purpose which will presently be made apparent, the ends of the wings 11 are bent at right angles, as at 13, to provide bracket portions at the ends of the plates 9. The permanent leaves of the binder are indicated by the numeral 14 and the temporary leaves are indicated by the numeral 15, and by reference to Figures 2 and 7 of the drawings, it will be observed that the inner edges of the leaves 14 abut against the inner faces of the respective plates 9, the leaves being arranged in two banks or groups, the leaves at their inner marginal portions being confined between the flange 11 of the plate 9 and a retaining means which will presently be described. At this point it will be evident that the back 3, due to its peculiar formation, imparts to the binder as a whole the appearance of what is known as a divinity circuit book. It will also be observed that the back is so arranged as to prevent any of the metallic parts of the binder coming in contact with a surface upon which the binder is disposed, and the back likewise serves to substantially conceal the mechanical parts of the binder.

It will be observed by reference to Figures

2, 3, 4 and 7 of the drawings, that there are a pair of the plates 9, and with each of these binder plates there is associated a binder member which is indicated in general by the numeral 16, which member is hinged, as will presently be explained, so that it may be swung into and out of position to clamp and bind the inner margins of the respective banks of permanent leaves 14. The ends of the plates 9 are formed with right angularly projecting terminal portions 17 which lie against the inner sides of the respective end portions 13 of the flanges 11 of said plates 9, and registering openings 18 are formed in the said portions 17 and 13 to accommodate a screw 18' which is threaded into a rectangular block 19 disposed against the inner side of the respective portion 17, the said block 19 being provided with a threaded opening 20. It will be evident at this point that there is a pair of the blocks 19 at each end of the binder back, and the relatively adjacent corners of the blocks of each pair are formed to provide rack segments 21 which mutually mesh. A shaft 22 is secured at its ends in openings 23 formed in the rack segment portions 21 of the blocks 19 at each side of the binder back, and these shafts 22, of course, extend parallel to each other, it being evident at this point that when the binder is opened or closed, the rack segments which are intermeshed, will rotate with relation to each other in a manner to insure of even opening and closing of the binder at its top and bottom and thus prevent any distortion thereof and any disarrangement of the binder leaves. Links 24 are arranged immediately inwardly of each pair of the rack segments 21 of the blocks 19 and are provided with openings 25 to accommodate the respective end portions of the shafts 22, so that the shafts are relatively spaced and braced at this point. Each plate 9 is formed along its free edge, at intervals, with pintle eyes 26 through which the shaft 22 extends. Each of the binding members 16 is formed from a metal plate or strip folded upon itself to provide plies 27 and 28, the ends of the ply 28 of each of the members being provided with flanges 29 which engage against the ends of the ply 27. The ply 27 of each of the members 16 is formed along its free edge at intervals with pintle eyes 30 which are interfitted with the pintle eyes 26 upon the respective plates 9 and pivotally embrace the respective shafts 22, and in this manner the members 16 are supported upon the shaft 22 for swinging movement with relation to the respective companion binding members comprising the plates 9 and their flanges 11.

The permanent binder leaves 14 are formed with perforations 31 in their inner marginal portions to accommodate binder posts 32 which are riveted or otherwise secured at one end to the inner side of the re-

spective flange 11, as indicated by the numeral 33 and at best shown in Figure 5 of the drawings. The posts 32 are preferably located near the ends of the respective flanges 11, and each post is provided at its free end with a circumscribing groove 34 providing a head 35. As illustrated most clearly in Figure 5 of the drawings, the plies 27 and 28 of each binder member 16 are relatively spaced throughout their end portions but are pressed together throughout their intermediate portions, and the end portions of the members 16, therefore, constitute flat-sided guideways 36 in each of which there is arranged a locking plate 37 formed near one end with a keyhole slot 38, the larger end of which is of a diameter to permit of passage of the head 35 therethrough, and the smaller end of which is of a diameter to embrace the neck of the head, which neck is formed by providing the circumscribing groove 34 in the free end of the respective post 32. By reference to Figure 5, it will be observed that the plies 27 and 28 of the members 16 are provided with openings 39 to accommodate the outer ends of the posts 32, and it will further be observed by reference to Figures 2, 5, 6 and 7 of the drawings that when the members 16 are swung to the position shown in Figure 5, or, in other words, in position confining or binding the inner margins of the respective banks of permanent leaves 14, and the plates 37 are shifted to the position shown in Figure 6, the walls of the keyhole slots 38 of the plates will have locking engagement with the outer ends of the respective posts 32, thereby preventing swinging movement of the members 16 to position to release the permanent leaves 14. Each locking plate 37 is yieldably held in locking position through the medium of a small wire spring 40 having one end 41 bearing against that end of the plate which is next adjacent the end of the binder back and opposite the end in which the keyhole slot 38 is formed; the other end portion of the spring being bent as at 42 to engage about the end of the adjacent flange 29, as best shown in Figures 6 and 9 of the drawings. The fold in the member 16 is cut away as at 43 so as to accommodate a small finger piece 44 which is formed at the adjacent edge of the plate 37 and which finger piece may be engaged by the finger nail or by a knife blade for the purpose of retracting the locking plate 37 to permit of release of the headed end of the respective post 32, when it is desired to swing the respective binding member 16 to position to permit of removal of any one or more of the permanent leaves 14, or the insertion of other leaves. In order to guide the plate 37 in its sliding movement, the edge thereof at which the finger piece 44 is formed, slidably fits in the fold which forms the plies 27 and 28 of the member 16, and a guide lug 45 is preferably stuck up from the ply 28 to engage the opposite longitudinal edge of the plate, for the purpose stated.

Each stack or group of permanent leaves 14 is further retained in place in the binder through the provision of binder posts 46 riveted at one end or otherwise secured, as at 47, to a strip 48 which is of metal and is provided along one longitudinal edge at 70 its intermediate portion with an upstanding flange 49 to embrace the folded edge of the respective binder member 16 at the intermediate portion of said member, the strip being provided at each end with an upstanding lug 50 which is engageable in a small opening 51 formed in the plies 27 and 28 of the respective members 16. The free ends of the posts 46 fit in openings 52 formed in the inner fold of the respective flange 11, and the posts fit through perforations 53 formed in the inner marginal portions of the binder leaves 14. While the strip 48 is not, in a sense, connected with the respective member 16 and, in fact, remains in position with its posts 46 engaging in the perforations 53 and the openings 52, when the said member 16 is swung about its respective shaft 22 to release the binder leaves 14, nevertheless, through the engagement of the lug 50 in the opening 51, and through the engagement of the flange 49 against the edge of the respective member 16, the strip is normally held substantially fixed with respect to the member 16, when the member is in position to retain the leaves 14 in place. Likewise, due to the engagement of the lugs 50 in the opening 51 and the engagement of the free ends of the posts 46 in the openings 52, the intermediate portions of the inner margins of the leaves 14 are held against displacement and, therefore, the posts 46 assist the posts 32 in retaining the leaves in proper assembled relation and against displacement. Of course, when it is desired to introduce or remove the leaves 14 in either section of the binder stack, this may be readily accomplished by first swinging the respective members 16 to position to clear the margins of the leaves 14, whereupon all of the leaves previously held by that section of the binder may be bodily removed, together with the strip 48 and posts 46 the latter still engaged in the openings 53 to prevent disarrangement of the leaves, or the strip 48 may be lifted to disengage the posts 46 from the openings 53 and at such time, any one or more of the leaves may be removed, the other leaves being retained in place by the posts 32. It will be evident that in this manner there is a minimum disarrangement of the leaves in introducing or removing leaves, and considerable time and labor is, therefore, saved.

The means provided for retaining in place the temporary leaves 15 preferably comprises

a series of counterpart retaining devices best illustrated in Figures 7 and 8 of the drawings. Each of these devices comprises a bracket member 54 preferably of resilient sheet metal and including a substantially flat strip-like body 55 provided at its opposite longitudinal edges with upstanding flanges 56 which are formed with openings 57 transversely aligned to accommodate the shafts 22, the flanges of the bracket members engaging relatively adjacent ones of the pintle eyes which serve to connect the plates 9 and binder members 16 with the shaft, and the said bracket members being, in this manner, substantially fixedly supported with relation to the said shaft. One of the retaining devices is preferably positioned between two pairs of posts 46, and in like manner one of the retaining devices is preferably positioned between a pair of the posts 46 and the adjacent pair of the posts 32, so that a symmetrical arrangement of the retaining devices for the permanent and temporary binder leaves is obtained. The numeral 58 indicates retaining fingers which are of arcuate form and one of which is associated with each of the bracket members 54. Each of the fingers 58 is provided at one end with an enlargement 59 having an opening 60 formed therein, and a pin 61 is inserted through the opening and riveted or otherwise secured at its ends in openings 62 formed in the flanges 56 at one end of the bracket member. The enlarged end 59 of the finger is formed with a flat surface 63 and with a similar surface 64, the two surfaces meeting at a ridge 65.

As stated, the body portion 55 is of resilient metal and the same is formed with parallel slits 66 providing between them a spring tongue 67 against which either of the flat surfaces 63 or 64 of the enlarged end 59 of respective finger 58 may squarely engage. The finger 58 is so formed that when its flat surface 63 is resting in engagement with the spring tongue 67, the free end of the finger, indicated by the numeral 68, will rest in engagement with the upper side of the body portion 55 of the bracket member 54 at that end of the said body portion opposite the end at which the tongue 67 is located, and in this position of the finger it is designed to retain in place the temporary leaves 15, the leaves being provided with perforations 69 adapting them to be fitted to the finger and retained thereby. On the other hand, when it is desired to remove any one of the leaves 15 or apply the leaves to the retaining fingers, the fingers may be swung bodily upwardly about their pivots so that the ridges 65 of their enlarged ends 59 will ride over the surfaces of the respective tongues 67 until the flat surfaces 64 of the enlarged ends 59 rest in engagement with the said tongues, whereupon the fingers will be held in an open

position to permit of the ready application of leaves to the fingers or removal of the leaves from the fingers. The plies 28 of the members 16 are recessed as indicated by the numeral 70, so as to accommodate the end portions of the members 54, and an opening 71 is formed in the ply 27 of one of the members 16 to accommodate the pivoted end of each respective finger 58, and similar openings 72 are formed in the corresponding ply 75 of the other member 16 to accommodate the free ends 68 of the fingers. It will be observed, by reference to Figure 7 of the drawings, that the pivoted and free end portions of each of the fingers are extended on an arc having the relatively adjacent shaft 22 as its center, the intermediate portion of the finger extending on a gradual curve connecting these two more arcuate portions. Therefore, the members 16 may be swung about the shafts 22 without in any way interfering with the fingers 58 or without any interference on the part of the fingers. Furthermore, when the binder is closed, as shown in Figure 4 of the drawings, the end portions of the members 54 will be accommodated in notches 73 formed in the margins of the leaves 14.

The leaves 15 are preferably provided with perforations 74 and 75, in addition to the perforations 69, and corresponding to the perforations 31 and 53 of the leaves 14, so that if it should be desired to do so, a number of the leaves 15 may be arranged within the front or within the back of the binder 90 as a whole to become a permanent part of the binder, in the same sense that the leaves 14 constitute a permanent part thereof.

In order that the binder may be locked closed or, in other words, in order that the two binder sections which carry the permanent leaves 14, may be locked together, and against unfolding, a latch spring 76 is provided and is disposed in a groove 77 formed in one edge of one of the blocks 19 110 at each end of the binder back, each spring having a portion 78 extending at right angles to its portion 76 and engaging in a groove in the next adjacent side or edge of the block, and a shorter portion 79 engaging in a similar groove 80 formed in that edge of the block opposite the first mentioned edge. In this manner, the springs are held assembled with their respective blocks inasmuch as the second and third mentioned edges of each block are engaged respectively against the flange 11 and plate 9 of the respective binder member 16. The portion 76 of each latch spring is extended beyond the remaining edge of the respective block and overturned to provide a hook 81 located opposite the rack segment 21 of the respective block. The hooked end 81 of each spring is, furthermore, preferably provided with a lateral finger piece 82, whereby the spring 130

may be sprung away from the block and out of engagement with the keeper of the latch device, which keeper comprises a lug 83 formed upon the end portion 17 of the opposing plate 9. Each block 19 which carries one of the springs 76, is preferably provided with an integral portion 84 which extends across the groove 77 and, consequently, across the portion 76 of said spring, so that the spring is somewhat reinforced at this portion and is prevented from springing outwardly from the groove to too great an extent.

Figures 12 and 13 of the drawings illustrate a modified form of latch for holding the two binder sections locked together and against unfolding, and in these figures, the numeral 85 indicates in general a latch spring which is secured at one end by a rivet 86 to the end of one binder section and is sprung outwardly from its secured end and maintains this position, as illustrated most clearly in Figure 13, due to its resiliency. The outer end portion of the latch spring is bent substantially at right angles, as at 87, to its shank portion and thence substantially at right angles to its portion 87 as indicated by the numeral 88, and the said portion 88 terminates in a hook which is indicated by the numeral 89. The hook 89 extends at an acute angle inwardly with relation to the portion 88, as clearly shown in Figure 13, and is adapted to engage behind the hooked end 90 of a keeper 91 carried by the corresponding end of the other binder section. By reference to the drawings, and more particularly to Figure 13, it will be understood that when the binder is closed, the hooked end 89 of the latch spring will ride over the end of the hook 90 of the keeper 91 and snap into engagement behind the said hook, thereby locking the binder sections in closed position and preventing accidental unfolding thereof. However, the sections may be readily unlocked by pressing inwardly against the outsprung portion of the latch spring, which portion is indicated by the numeral 92, so as to disengage the hooked end 89 of the latch spring from the keeper hook 90. As in the case of the form of latch previously described, one of the latches shown in Figures 12 and 13, would, of course, be located at each end of the binder, so that the binder will be locked closed at both ends, when the latch springs are engaged with their respective keepers and, on the other hand, it will be a simple matter to free the latches to permit of opening of the binder by merely pressing against the portions 92 of the latch springs, whereupon the binder sections will naturally fall to an open position if the binder or book as a whole is resting on its back. In order that the latch spring 85 of each latch may be

adjusted as occasion may require, an adjusting screw 93 is fitted loosely through an opening in the outwardly sprung shank portion of the latch spring and is threaded into the corresponding block 94 of the respective binder sections, it being understood that adjustment of this spring may serve to vary the angular position of the outwardly sprung portion of the spring with relation to the face of the binder section part upon which it is mounted. Thus, if desired, the latch springs may be adjusted so as to substantially clear the keepers if it is desired to render the latches temporarily inactive, or only one of the springs may be so adjusted, and, on the other hand, either or both of the springs may be adjusted so as to effect proper engagement of the hooked ends with the respective keepers.

As an example of the manner of using the binder, presuming that it is to be used by a minister, he may arrange the printed text leaves of the Bible within the binder sections 16 in such a manner that that portion of the text on which he is to deliver his sermon will be presented, for example, at the right in Figures 1 and 2 of the drawings, as designated by the numeral 14 in each of these figures. In preparing his sermon, he may make notes upon the temporary leaves 15 and, having arranged the text leaves in the manner stated, will arrange his written notes, contained upon the leaves 15, in the temporary binder section comprising the members 58, as for example as shown in Figures 1 and 2, and indicated by the numeral 15. Therefore, when he is prepared to deliver his sermon and opens the binder, the printed text will be before him and beside it the memoranda or note leaves upon which he has made his notes, and it will be evident that this is an exceptionally convenient arrangement.

Having thus described the invention, what I claim is:

1. In a loose leaf binder, binder sections each comprising a relatively fixed member having angularly disposed portions to accommodate the margins of an assemblage of leaves, means hingedly connecting the members of the two sections, each section further comprising a swingingly adjustable binder member to likewise engage the margins of the leaves, retaining means for the leaves associated with the members of each section, and means supported between the said binder sections and adjustable independently of the second-mentioned members of said sections, to accommodate and retain in place a plurality of temporary leaves.

2. In a loose leaf binder, binder sections embodying means for embracing and retaining in place the margins of substantially permanent leaves, means hingedly connecting the sections for relative swinging ad-

- justment whereby the binder may be completely closed and may likewise be opened to flat condition, means upon the sections for effecting uniform swinging adjustment 5 of the sections throughout their length, and means adjustable independently of the sections for accommodating and retaining in place, between the said sections, the margins of a plurality of temporary leaves.
- 10 3. In a loose leaf binder, binder sections, parallel shafts, each binder section including a member embodying angularly disposed portions to accommodate the margins of an assemblage of substantially permanent leaves
- 15 each section further including a binder member swingingly adjustably mounted upon the respective one of the shafts, means upon the first mentioned member of each binder section supporting the respective 20 shafts, means connecting the shafts in parallelism, coacting means upon the members of each binder section for retaining the margins of leaves arranged therebetween, and coacting rack segments upon the first 25 mentioned members of the said sections for effecting uniform movement of said sections about their respective shafts in their swinging adjustment.
4. In a loose leaf binder, binder sections, 30 parallel shafts, each binder section including a member embodying angularly disposed portions to accommodate the margins of an assemblage of substantially permanent leaves, each section further including a 35 binder member swingingly adjustably mounted upon the respective one of the shafts, means upon the first mentioned member of each binder section supporting the respective shafts, means connecting the 40 shafts in parallelism, coacting means upon the members of each binder section for retaining the margins of leaves arranged therebetween, coacting rack segments upon the first mentioned members of the said sections 45 for effecting uniform movement of said sections about their respective shafts in their swinging adjustment, and means supported by the shafts and adjustable independently of the first mentioned binder sections for accommodating and retaining in place a 50 plurality of temporary leaves.
5. In a loose leaf binder, means for binding and retaining the margins of binder leaves comprising a relatively fixed section 55 having angularly disposed portions to accommodate the margins of the leaves, a section swingingly connected with the first mentioned section and movable into and out of position to confine the margins of the 60 leaves, leaf-retaining posts upon the fixed section, and a locking means upon the movable section coacting with the said posts and adjustable into and out of position to have locking engagement with the said posts.
- 65 6. In a loose leaf binder, means for con-

fining and retaining the margins of leaves to be bound comprising a fixed member having a relatively angularly disposed portion to accommodate the margins of the leaves, a member swingingly adjustably connected with the first mentioned member, leaf-retaining posts upon the fixed member having headed ends, slideable locking plates upon the movable member having keyhole slots arranged in one position of adjustment of the plates to permit of passage of the headed ends of the posts and, in another position of adjustment of the plates, to have locking engagement with the headed ends of the posts, means whereby the locking plates may be slideably adjusted, and means yieldably holding the locking plates in locking position.

7. In a loose leaf binder, means for confining and retaining the margins of leaves to be bound comprising a fixed member having a relatively angularly disposed portion to accommodate the margins of the leaves, a member swingingly adjustably connected with the first mentioned member, leaf-retaining posts upon the fixed member having headed ends, slideable locking plates upon the movable member having keyhole slots arranged in one position of adjustment of the plates to permit of passage of the headed ends of the posts and, in another position of adjustment of the plates, to have locking engagement with the headed ends of the posts, means whereby the locking plates may be slideably adjusted, and means yieldably holding the locking plates in locking position, said means comprising a spring fixed with relation to the movable member and engaging one end of the respective locking plate.

8. In a loose leaf binder, means for accommodating and retaining in place the margins of a plurality of leaves to be bound, said means comprising a relatively fixed member having relatively angularly disposed portions to accommodate the margins of the leaves, a binder member swingingly connected with the first mentioned member and movable into and out of position to engage and confine the margins of leaves, binder posts upon the fixed member for retaining the leaves, locking means upon the movable member for coaction with the posts to lock the movable member in leaf-retaining position, and means removably associated with the movable member for engaging the leaves in a manner to maintain the same in assembled relation upon their removal from the said binder posts.

9. In a loose leaf binder, means for accommodating and retaining in place the margins of a plurality of leaves to be bound, said means comprising a relatively fixed member having relatively angular disposed

portions to accommodate the margins of the leaves, a binder member swingingly connected with the first mentioned member and movable into and out of position to engage and 5 confine the margins of the leaves, binder posts upon the fixed member for retaining the leaves, locking means upon the movable member for coaction with the posts to lock the movable member in leaf-retaining position, a member removably assembled with 10 the movable binder member, and binder posts carried by the last mentioned member for retaining the leaves in assembled relation at the time of their disengagement from the 15 first mentioned binding posts.

10. In a loose leaf binder, binder sections each embodying means for accommodating and retaining in place a plurality of relatively permanent leaves, means hingedly 20 connecting said sections whereby the binder may be opened and closed, bracket members supported adjacent the connections between the said sections and each embodying a resilient tongue, and a leaf-engaging finger 25 pivotally connected at one end with each respective bracket member and having angularly disposed flat surfaces at its said end to engage against the resilient tongue of the 30 respective bracket member in positions of swinging adjustment of the finger, each finger being of substantially arcuate form

and bridging the connection between the said sections, whereby a plurality of temporary leaves may be accommodated and retained in place between the sections. 35

11. In a loose leaf binder, binder sections each comprising a binder member including relatively right angularly disposed portions, means hingedly connecting said members, a binder member swingingly connected with 40 the said hinged means for each section and coacting with the first mentioned respective member of the sections to confine and retain the leaves to be bound, cover leaves having their inner marginal portions disposed beside 45 corresponding portions of the first mentioned members of the binder sections, a back of flexible material folded at opposite sides of its median line to provide marginal flaps disposed against said inner marginal portions of the cover leaves, plates disposed against the inner sides of the said flaps of the back, means uniting the plates, the said flaps of the back, the said inner marginal portions of the cover leaves, and the 50 said portions of the first mentioned members of the binder sections together, and coacting means upon the members of each binder section for retaining the binder leaves assembled therewith. 55

In testimony whereof I affix my signature.

HENRY B. JENNINGS, JR. [L. S.]
